United States Patent Office

Des. 182,920
Patented May 27, 1958

182,920

FOUNTAIN

Tadashi Nakamura, Takasaki-City, and Tometaro Sueki, also known as Yoshihisa Sueki, Sumida-ku, Tokyo, Japan, assignors to Fred Roberts Company, San Francisco, Calif., a corporation of California

Application October 9, 1957, Serial No. 48,020

Term of patent 7 years

(Cl. D91—4)

FIG. 1

FIG. 2

FIG. 3

Fig. 1 is a top plan view of a fountain showing our new design;

Fig. 2 is a side elevational view of the fountain, the other side being substantially the same; and

Fig. 3 is a bottom plan view of the fountain.

We claim:

The ornamental design for a fountain, as shown and described.
